SUN DIAL

Louis K. Loewenstein, Elkins Park, Pa.

Application October 22, 1956, Serial No. 43,458

Term of patent 14 years

(Cl. D42—7)

Figure 1 is a side elevational view of a sun dial showing my new design;

Figure 2 is a rear elevational view; and

Figure 3 is a top plan view thereof.

I claim:

The ornamental design for a sun dial, substantially as shown.
